UNITED STATES PATENT OFFICE.

ELI MILLER, OF CANTON, OHIO.

FENCE-MAKING MACHINE.

SPECIFICATION forming part of Letters Patent No. 337,420, dated March 9, 1886.

Application filed August 21, 1885. Serial No. 174,987. (Model.)

To all whom it may concern:

Be it known that I, ELI MILLER, a citizen of the United States, and a resident of Canton, county of Stark, State of Ohio, have invented a new and useful Improvement in Fence-Making Machines, of which the following is a full, clear, and exact description, reference being had to the accompanying drawings, making part of this specification.

My invention relates to improvements in machines for making picket or slat fences, in which wires to embrace the slats are fed through hollow twisting-spindles from spools mounted on and revolving with the spindles, said spindles being rotated in one direction by a train of connecting gear-wheels actuated by a hand-crank or other source of power.

My invention further relates to and consists in providing a rotary reciprocating presser-bar.

My invention further relates to and consists in devices for forcing the slats laterally into position and holding them while the wires are being twisted.

A further object of my invention consists in providing a removable twister-head having separate ways for the passage of the wire, and lips to bear against the wire while being twisted.

With these objects in view my invention consists in certain features of construction and combination of parts hereinafter described, and set forth in the claims.

In the accompanying drawings, Figure 1 is a plane view of my invention. Fig. 2 is a side elevation showing the working parts in position. Fig. 3 is a view of enlarged section of side elevation. Fig. 4 is a view of the slat-driver. Fig. 5 is an enlarged detached view of the bar D, having the adjustable plate thereon. Fig. 6 is a sectional view through the spool-spindle. Fig. 7 is an end view of one of the spindles, and Fig. 8 is an enlarged view in cross-section of the presser-bar and adjacent parts.

The several parts of the supporting frame are represented by the letters *a a*, which may be varied according to circumstances or judgment. Cross-pieces *b b* form the frame for the twisting-spindles *A* and gear-wheels *B*. The spindles and gear-wheels are duplicates, and

will not require separate description. The movable frame-pieces *C C* are connected by a cross-piece, *D*, which forms a support for the platform-strips *ff f*. The twisting-spindles *A* are mounted on the cross-frame *b b*, and provided with gear-wheels *B*, placed at such distances apart as to allow them to engage with each other. The spindles are hollow and divided, by a partition, *H*, into two parts or guideways for the passage of the wires, so that they may be kept separate and avoid liability to become entangled one with the other. The division *H* extends back and forms a support for the wire-spools *J*. Gear-wheels *B'* and *B''* make out the train of gear. *B'* is mounted on a shaft having an actuating-crank *G*, by which the twisting-spindles may be rotated. The spindles are provided with a removable twister-head, *A'*, having two passage-ways, *a' a'*, for the wire, which coincide with the ways in the spindles, and have lips that extend out from the body of the head to bear against the wire during the operation of twisting.

The wire-spools *J* are mounted on the extension *H* of the spindles, and secured by a through-bolt provided with thumb-nuts *i*, which may be turned against the ends of the spools *J*, so as to give to the wire a tension that will keep it taut while the slats are being forced into position and the wires twisted about it.

K is a shaft on which the fence is rolled as the work progresses. The wires may be secured to the shaft in notches or by hooks. This winding shaft or reel has bearings located on the frame, that are open on one side so that the shaft may be easily removed.

Outside of the frame there is mounted on the reel-shaft a ratchet-wheel, *L*, which is operated by the foot-treadle *S* and the pawl *S'*, the foot-lever being pivoted over the pin *S'*. The rack-wheel is held in position by a pawl, *S''*, (shown in these drawings,) which is attached to the side of the frame.

The frame-piece *C*, Fig. 2, is adjustable in the slots *c*, so as to adapt the machine for making fence differing in size of mesh and spaces between slats. A cross-piece, *D*, (see Fig. 5,) is provided with an adjustable plate, *w*, on its front side that may be set so as to form a slight rib or ledge, the upper edge of which

may extend up above the face of the table for the purpose of bending the wire snug around the corners of the slat, and it may be put on in one continuous piece, or in sections, if preferred. The piece D unites the adjustable posts or frame-pieces C, and is a support for the table-straps f.

The presser-bar N is mounted on a shaft, O, and rotated in boxes P, which are adjustable 10 in the box-frame P, and rest against a gum spring, P'. By the use of this spring slats of an uneven thickness may be used, as the presser-bar will rise slightly, the gum spring P' yielding to the pressure, and will follow 15 down in case of a thin slat, and will in either case hold the slat and wire, pressing the wire tight upon the slats.

The presser-bar may be made of one continuous piece extending across the machine, 20 or may be mounted on the shaft in sections, leaving an open space on the shaft O between the wires. The drivers Q (see Fig. 4) have an adjustable connection with and form a part 25 of the presser-bar N, by which they may be adapted to bend the wire down from above snug to the corner of the slat, corresponding with the bend made by the ledge on the table, heretofore described, thus causing the wires to fit close to the slats, as well as to hold the 30 wires perpendicular one above the other and straight across the slat, and act as drivers, by which the slats may be driven hard against the twisted wire chain, and at the same time firmly held between the presser-bar and the 35 table while the wire is being twisted on the front side between the fingers Q' and Q'' of the driver.

On the presser-bar N there are mounted two or more stops, T, which may be adjusted to 40 the presser-bar by thumb-screws or other devices, so as to stop the web at the desired point, as a gage to regulate the space between slats. When the presser-bar is thrown up, the stops are brought down just in front of the slat 45 i', (see dotted lines, Fig. 3,) and the web moved by the foot-lever S until the slat m strikes the stop T and arrests its movement; and when the presser-bar is brought into action the stops are lifted out of the web, so that 50 one lever will operate the presser-bar and the stops.

The operation of the machine is as follows: The wire is wound upon a reel, which is supported by and rotates about the spindle W on 55 one corner of the frame. On the opposite corner of the frame is mounted a crank-shaft and gear-wheel that engages with a pinion on a spool-spindle on which the spool J may be placed. By connecting the wire on the reel

to the spool and turning the crank the wire 60 will be transferred from the reel to the spool. A proper amount of pressure will be required on the hub of the reel, so that the wire may be wound tight on the spool. The spools are then placed on the spindles as shown in Fig. 65 1, the wires passed through the spindle, and the ends of the two wires from each spindle are twisted together. A single wire is then attached to the ends of the twisted wire extending to the reel. The presser-bar is thrown 70 up, as seen in Fig. 3 and shown by the dotted lines. A slat is placed in the machine between the wires, as shown by letter h, when the lever R is thrown over from x to z, bringing the presser-bar down, as shown, and the drivers 75 catching and driving the slat into position, as shown at g, Fig. 3, where it is held during the operation of turning the crank and twisting the wires, after which the lever is thrown back to the place of beginning, releasing the slat. 80 The foot may then be placed on the lever S and pressed down, which, by the pawl and rack, will move the reel so as to wind up the web just enough to make room for another 85 slat, or until arrested by the stops T. 85

Having thus fully described the nature and operation of my invention, what I desire to secure by Letters Patent is—

1. In a fence-making machine, a presser-bar having a reciprocating rotary movement 90 and an actuating-lever, substantially as described, and for the purpose set forth.
2. In a fence-making machine, the combination of the presser-bar N, the drivers Q, and the actuating-lever R, substantially as described, and for the purpose set forth. 95
3. In a fence-making machine, the combination of an adjustable frame composed of the cross-bar D, adjustable plate W, adjustable side pieces, C, and the presser-bar N, substantially as described, and for the purpose set forth. 100
4. In a fence-making machine, the combination, with the presser-bar N, the adjustable journal-box P, and spring P', substantially as described, and for the purpose set forth. 105
5. In a fence-making machine, the combination of the presser-bar N, the adjustable drivers Q, actuating-lever R, and the adjustable stops T, substantially as described, and for the purpose set forth. 110

In testimony whereof I have hereunto set my hand this 15th day of August, A. D. 1885.

ELI MILLER.
